United States Patent Office

Des. 187,874
Patented May 10, 1960

187,874

SNOW PLOW BLADE

Arthur B. Cross, Winnetka, Ill., assignor to General
Brands, Inc., Chicago, Ill., a corporation of Illinois

Application August 18, 1958, Serial No. 52,273

Term of patent 14 years

(Cl. D35—2)

FIG. 2.

FIG. 3.

FIG. 5.

FIG. 4.

Fig. 1 is a rear perspective view of a snow plow blade showing my new design;

Fig. 2 is a front elevational view thereof;

Figure 3 is a rear elevational view thereof;

Figure 4 is a left side elevational view thereof, a portion of the handle socket being broken away for convenience of illustration; and

Figure 5 is a right side elevational view thereof.

I claim:

The ornamental design for a snow plow blade, as shown.
